UNITED STATES PATENT OFFICE.

PETER N. LANDINE, OF MILFORD, CONNECTICUT.

DESIGN FOR ORNAMENTAL TUBING.

49,667.

Specification for Design.

Patented Sept. 19, 1916.

Application filed February 15, 1916. Serial No. 78,545. Term of patent 3½ years.

To all whom it may concern:

Be it known that I, PETER N. LANDINE, a citizen of the United States of America, residing at Milford, Connecticut, have invented a new, original, and ornamental Design for Ornamental Tubing, of which the following is a specification, reference being had to the accompanying drawing, forming part thereof.

In said drawing: Figure 1 is a perspective view of a piece of ornamental tubing embodying my invention. Fig. 2 is an end view of the same.

I claim:

The design for ornamental tubing as shown or any imitation thereof.

PETER N. LANDINE.
